UNITED STATES PATENT OFFICE.

JOHN GEORGE KNUCK, OF WOODHAVEN, NEW YORK.

ENVELOP.

1,228,218.

Specification of Letters Patent.

Patented May 29, 1917.

Application filed December 9, 1916. Serial No. 135,976.

To all whom it may concern:

Be it known that I, JOHN G. KNUCK, a citizen of the United States, and a resident of the city of New York, Woodhaven, borough 5 of Queens, in the county of Queens and State of New York, have invented a new and Improved Envelop, of which the following is a full, clear, and exact description.

This invention relates to envelopes of that 10 type which can be opened at one end for postal inspection and which are open at the top for facilitating the insertion of mail matter, there being a sealing flap for closing the top after the insertion.

15 The invention has for its general objects to improve the construction of envelopes so as to be more durable and serviceable, and which when sealed will insure the inspection end against accidental opening, while 20 at the same time permitting the postal authorities to readily open the envelop for inspection.

A more specific object is to improve the construction of inspection envelopes of the 25 type disclosed in United States Letters Patent 1,196,245, granted to me August 29, 1916, wherein interlocked unsealed flaps permit of the opening of the envelop, the improvement being in the provision of an 30 auxiliary or secondary flap on the doubled interlocking flap, whereby the secondary flap can be turned down over the outside of the back face of the envelop at one corner thereof to reinforce the envelop at this portion 35 and prevent the same from being accidentally opened, such secondary flap being normally concealed under the sealing flap of the envelop when the latter is pasted down.

With such objects in view, and others 40 which will appear as the description proceeds, the invention comprises various novel features of construction and arrangement of parts which will be set forth with particularity in the following description and 45 claims appended hereto.

In the accompanying drawing, which 50 illustrates one embodiment of the invention and wherein similar characters of reference indicate corresponding parts in all the views,

Figure 1 is a back view of an envelop with a top or sealing flap in open position;

Fig. 2 is a back view of the envelop with the upper corner spread open to illustrate 55 the details of construction;

Figs. 3 and 4 are sectional views respec-

tively on the lines 3—3 and 4—4, Fig. 1; and

Fig. 5 is a plan view of the blank from 60 which the envelop is made.

Referring to the drawing, 1 designates the front of the envelop, 2 the back, 3 the top or sealing flap, 4 the flap on the end of the back 2 for sealing one end of the envelop, and 5 and 6 interlocking flaps on the 65 back and front 1 and 2 for closing the other end of the envelop. The flap 6 is approximately twice the length of the flap 5 and is doubled so as to form a pocket that lies within the body of the envelop, and into 70 which the flap 5 is folded, as clearly shown in Fig. 2. The flap 6 has a secondary flap 7 formed by a triangular extension at the top edge of the flap 6, said extension projecting above the top edge of the back 2 and 75 being adapted to fold outwardly and downwardly over the back face of the back 2, as clearly shown in Fig. 1. This serves to materially reinforce the corner of the envelop 80 where the open top meets the openable end of the envelop and insures the envelop maintaining its form during the insertion of the contents. When the top flap is folded down and sealed it covers the locking corner flap 7, 85 as indicated by the dotted line 8, Fig. 1. 85

From the foregoing description taken in connection with the accompanying drawing, the advantages of the construction and method of operation will be readily understood by those skilled in the art to which the 90 invention appertains, and while I have described the principle of operation, together with the article which I now consider to be the best embodiment thereof, I desire to have it understood that the article shown is 95 merely illustrative and that such changes may be made when desired as fall within the scope of the appended claims.

Having thus described my invention, I claim as new and desire to secure by Letters 100 Patent:

1. An envelop comprising a body having a sealing flap along one edge, a double flap connected with one face of the envelop and disposed within the body, a flap connected 105 with the other face and normally disposed within the folded flap, said folded flap having an extension folded in the line of fold of the folded flap and forming a secondary flap extending out of the body and folded 110 downwardly against one of the faces thereof and lying under the sealing flap.

2

2. An envelop comprising front and back sections, a double flap extending along the edge of one section and normally lying between the sections, a flap extending along the corresponding edge of the other section and entering the pocket formed by the folded flap, said folded flap having a triangular

secondary flap folded on the line of fold of the folded flap and further folded back against the outside of one of the sections, 10 and a sealing flap on the said section having the double flap, adapted to cover the secondary flap.

JOHN GEORGE KNURCK.

Copies of this patent may be obtained for five cents each, by addressing the "Commissioner of Patents, Washington, D. C."
